UNITED STATES PATENT OFFICE.

GEORGE DOUGLAS LEECHMAN, OF LONDON, ENGLAND.

ADJUSTABLE WRENCH.

1,413,125.

Specification of Letters Patent. Patented Apr. 18, 1922.

Application filed March 22, 1921. Serial No. 454,355.

To all whom it may concern:

Be it known that I, GEORGE DOUGLAS LEECHMAN, a subject of the King of Great Britain, residing at Lamb Building, Temple, London, E. C. 4, England, have invented a new and useful Adjustable Wrench, of which the following is a specification.

Adjustable wrenches commonly have three defects:—first, they have a milled nut adjustment affording an inadequate grip; second, the adjustment is very apt to slack back; and third, the jaws are liable to gape owing to the design failing to provide means for compensating for loose fitting of the parts of the wrench. My invention has for one object to overcome the above defects; another object is to provide a wide range of jaw opening in a single instrument. And my invention consists essentially in an adjustable wrench comprising two longitudinal members of similar form and size which cross each other, which have one or both pairs of ends adapted to serve as jaws, and which are adapted to be moved both laterally and angularly relatively to one another by means applied at points on both sides of the point of crossing, such means being capable of operation independently of each other.

In order that my invention may be properly understood I will further describe the same, by way of example, with the aid of the accompanying drawing, wherein:—

Figure I, is an elevation and Figure II is an edge view of a wrench constructed according to my invention.

Figure III, is an edge view and Figure IV is an end view, showing a modified construction.

Figure V is a transverse section on the line indicated by the arrows in Figure III. Similar numerals refer to similar parts in all the figures.

Referring to Figures I and II, I take two steel strips 1 and 2 of the form shewn, the ends 3, 4 and 5, 6 of each strip being off-set relatively to one another. The intermediate parts 7, 8 of the two strips are inclined relatively to the end parts and are also bent out of the plane of the said end parts, so that when the two strips are placed in position crossing one another, the said intermediate parts 7 and 8 will clear one another, while all the end parts 3, 4, 5 and 6 lie in the same plane. The opposing edges 9, 10 and 11,

12 of the end parts of the strips normally lie parallel to one another and form the faces of the jaws of the wrench.

Given the strips in the positions indicated in Figure I, it will be obvious that by moving the said strips laterally relatively to one another, the opening of one pair of jaws will be increased while the opening of the other pair will be correspondingly decreased; and further, by suitably recessing one pair of jaws, say 11, 12, the minimum opening of this pair may be made to equal or nearly equal the maximum opening of the other pair 9, 10, thus affording a large total range of opening in the one instrument. If it be not desired that the wrench shall be capable of closing to zero, then both pairs of jaws may be recessed, the recessing being so proportioned that one pair of jaws will close to the desired minimum, and the opening of the other pair being modified accordingly.

The lateral movements of the strips may be conveniently effected with the aid of two screw-threaded bolts 13, 14 and nuts 15, 16 as shewn. The head ends of the bolts may be secured in the respective strips by pins or rivets 17. The bolts and nuts are adapted to adjustably limit the opening of the respective pairs of jaws. The bolts and bolt holes are proportioned freely so that the parts of the wrench can adapt themselves to irregular handling and to the gripping action hereinafter referred to; but broadly, in adjusting the wrench, one nut, say 15, should be screwed back so that the corresponding jaws 9, 10 may open before screwing up the other nut 16 to close its pair of jaws 11, 12 on to the object to be operated on.

The opening of the jaws may be assisted by any suitable springs pressing outwards against the strips, such as the spiral springs 18, which are for convenience threaded on to the bolts 13, 14 and are let into the bolt holes which are counterbored to receive them as shewn in dotted lines in Figure I.

In use, the wrench is applied and adjusted to the nut or other object to be operated upon by manipulating the nuts 15 and 16 as above indicated, the large or the small pair of jaws being employed according to the size of the object. After the pair of jaws is primarily adjusted to the object therein by the bolt and nut adjacent thereto, a further grip is obtained by slightly tightening the nut at the other end of the wrench; this

action causes the two strips to make a small angular movement, roughly about a point in the first bolt as centre, and so closes the jaws firmly upon the object, takes up possible 5 gaping in the jaws and serves as a lock to prevent the primary adjustment slackening back.

According to the modification shown in Figures III, IV and V, each strip 1 and 2 10 is built up of two similar parts 1¹ and 2¹, 2² pressed out of sheet metal and connected by riveting or other suitable means. This construction is advantageous in reducing the extent to which the members need be bent in 15 order to cross each other, in reducing the machining incidental to the fitting of the bolts and springs, and in facilitating the provision of fortified or hardened jaw pieces, such as 19, 20.

20 If desired, one or both pairs of jaws may be somewhat inclined to the centre line of the wrench.

I claim:

1. In an adjustable wrench, the combination 25 of two longitudinal members of similar form and size which cross each other, jaws at one pair of ends of the said members, and means applied at points on both sides of the point of crossing for moving the said members laterally relatively to one another.

2. In an adjustable wrench, the combination 35 of two longitudinal members of similar form and size which cross each other, jaws at both pairs of ends of the said members, and means applied at points on both sides of the point of crossing for moving the said members laterally relatively to one another.

3. In an adjustable wrench, the combination 40 of two longitudinal members of similar form and size which cross each other, jaws at one pair of ends of the said members, and means applied at points on both sides of the point of crossing for moving the said members laterally and angularly relatively to one another.

4. In an adjustable wrench, the combination 50 of two longitudinal members of similar form and size which cross each other, jaws at both pairs of ends of the said members, and means applied at points on both sides of the point of crossing for moving the said members laterally and angularly relatively to one another.

5. In an adjustable wrench, the combination 55 of two longitudinal members of similar form and size which cross each other, jaws at one pair of ends of the said members, and means applied at points on both sides of the point of crossing for moving the said members, the means on one side of the point of crossing being independent of the means on the other side of the point of crossing.

6. In an adjustable wrench, the combination 65 of two longitudinal members of similar form and size which cross each other,

jaws at both pairs of ends of the said members, and means applied at points on both sides of the point of crossing for moving the said members, the means on one side of the point of crossing being independent of 70 the means on the other side of the point of crossing.

7. In an adjustable wrench, the combination 75 of two longitudinal members which cross each other, jaws at one pair of ends of the said members, and, on each side of the point of crossing, a screw-threaded bolt applied to one member and a nut applied to the bolt and adapted to operate on the other member.

8. In an adjustable wrench, the combination 85 of two longitudinal members which cross each other, jaws at both pairs of ends of the said members, and, on each side of the point of crossing, a screw-threaded bolt applied to one member and a nut applied to the bolt and adapted to operate on the other member.

9. In an adjustable wrench, the combination 90 of two longitudinal members which cross each other, jaws at one pair of ends of the said members, means applied at points on both sides of the point of crossing for moving the said members laterally relatively to one another, the means on one side of the point of crossing being independent of the means on the other side of the point of crossing, and means for assisting the opening of the pairs of ends of the said members.

10. In an adjustable wrench, the combination 105 of two longitudinal members which cross each other, jaws at both pairs of ends of the said members, means applied at points on both sides of the point of crossing for moving the said members laterally relatively to one another, the means on one side of the point of crossing being independent of the means on the other side of the point of crossing, and means for assisting the opening of the pairs of ends of the said members.

11. In an adjustable wrench, the combination 115 of two longitudinal members which cross each other, jaws at one pair of ends of the said members, means applied at points on both sides of the point of crossing for moving the said members laterally relatively to one another, the means on one side of the point of crossing being independent of the means on the other side of the point of crossing, and spiral compression springs interposed between the said members.

12. In an adjustable wrench, the combination 125 of two longitudinal members which cross each other, jaws at both pairs of ends of the said members, means applied at points on both sides of the point of crossing for moving the said members laterally relatively to one another, the means on one 130

side of the point of crossing being independent of the means on the other side of the point of crossing, and spiral compression springs interposed between the said members.

13. In an adjustable wrench, the combination of two longitudinal members of sim-

ilar form and size which cross each other, recessed jaws at one pair of ends of the said members, and means applied at points 10 on both sides of the points of crossing for moving the said members laterally relatively to one another.

GEORGE DOUGLAS LEECHMAN.
